UNITED STATES PATENT OFFICE.

EUGENE GREGORY, OF ANN ARBOR, MICHIGAN, ASSIGNOR OF ONE-TENTH TO
EDWARD H. SAIER, OF LANSING, MICHIGAN.

BALLOT MARKER AND SETTER.

Application filed January 25, 1923. Serial No. 614,787.

This invention relates to balloting mechanism and its object is to provide means whereby voters may readily designate upon ballots of any size the candidates for whom they wish to vote and have the same registered and counted in absolute secrecy and certainty. In its entirety the invention will include three interdependent mechanisms. The first is what I designate a ballot or ticket-marker whereby a voter indicates or designates just the candidate for which he wishes to vote by means of a movable object preferably a ball, mechanism being provided for controlling in motion, and precisely locating, small colored balls, and permitting them to be seen at proper intervals and places by the elector, while he is voting, and covering them from any possible observation after they have been rolled to juxtaposition with the selected names on the tickets. Each ball ticket handler or setter carries a printed ballot, preferably arranged in sections so that each candidate's name appears on this ballot and enough movable balls are provided to enable the voter to vote for the legal number of candidates and he can readily place a ball opposite the name of any candidate on the entire ballot for which he wishes to vote up to the legal number of votes permitted. In connection with the ball ticket-marker I employ what I designate a ticket-handler or setter whose use is essential in order to enable the ballot on the ball ticket-marker to be properly marked by the voter. The ball ticket marker is automatically locked when it is separated from the ticket handler or setter so that it can not be manipulated but when it is properly placed in the ticket-handler or setter the latter causes automatic release of the operative parts of the ball ticket marker and the voter can then adjust the objects or balls to designate all the candidates for whom he wishes to vote and then when he opens the ticket handler to remove the ticket-marker therefrom the parts of the latter are automatically again locked and remain locked until the ballot has been placed in a registering machine or, what I term a vote counter, which latter operates to register a vote for every candidate opposite whose name the voter has placed a ball in the ballot and before the ballot can be removed from the counter

and after it has been registered the ballot is restored to normal blank condition and the parts thereof become locked in such position until the ballot has been again placed in the ballot-handler.

To enable others skilled in the art to adapt and use the invention I will explain one practical embodiment of the ballot-marker and the ballot-handler as illustrated in the accompanying drawings and summarize in the claims the essentials of the invention and the novel features of construction and novel combinations of parts for which protection is desired.

In said drawings:

Fig. 1 is a top plan view partly broken away of a ballot in position in the ballot setter. 70

Fig. 2 is a top plan view of the ballot detached partly broken and part of the ballot casing being removed.

Fig. 3 is a transverse section on the line 3—3 Fig. 2. 75

Fig. 4 is a detail view of part of the ball locking mechanism.

Fig. 5 is a detail transverse section on the line 5—5 of Fig. 4. 80

Fig. 6 is a section on the line 6—6 Fig. 3.

Fig. 7 is a longitudinal section on the line 7—7 Fig. 2.

Fig. 8 is a transverse section on the line 8—8 Fig. 2.

Fig. 9 is a detail bottom plan view of part 85 of the ballot the bottom plate removed.

Fig. 10 is a detail partly sectional view of a part of the ball locking device.

Fig. 11 is a detail view similar to Fig. 3 but showing the ball locking bars in retracted position. 90

Fig. 12 is a detail view of part of the ball spacing plates of the ballot.

Fig. 13 is an end elevation of the ballot setter with the ballot being indicated in dotted lines. 95

Fig. 14 is a detail section on the line 14—14 Fig. 1.

Fig. 15 is a detail view of the mechanism in the ballot setter for actuating the ballot cover plate 5. 100

Fig. 16 is an enlarged partial end elevation of the ballot setter.

Fig. 17 is a section on the line 17—17 Fig. 1.

Fig. 18 is a detail view showing mechanism for locking the bar 6^c in position.

The ballot-marker comprises a preferably rectangular shell box-like structure having a side frame 1 and a bottom 1^a. This frame may be made of any suitable material but is preferably made of sheet aluminum for purposes of lightness and strength so the parts can be readily pressed out of sheet metal. Secured on the bottom 1^a within the frame is a plate 2 (Fig. 3) which may be provided with parallel ribs 2^a (Fig. 7) which are spaced apart and guide longitudinally movable channel bars 6 (Figs. 3 and 7) hereinafter referred to. Supported upon the plate 2 is a plate 3 (Figs. 7 and 8) which is provided with a series of transverse corrugations forming the lower side of ball guiding grooves G for guiding movable objects hereinafter referred to. Above the plate 3 is a similar corrugated plate 4 so disposed that the corrugations in the plate 4 are opposite the corrugations in the plate 3 and thus the corresponding corrugations form channels or guideways G for the balls hereinafter referred to. These plates may be supported in the box in any suitable manner.

Extending transversely of the guideways G, are corrugations in the plates 3 and 4, and beneath the plate 3 are plates 6, (Figs. 3, 7 and 11) U-shaped in cross section but having their side flanges serrated as at 6^a these serrations approximately corresponding in size and distance apart with the grooves in the plate 3. The U-shaped plates are guided by and between the ribs 2^a on the plate 2; and to permit longitudinal movement of the plates 6 the plate 3 has transverse slits indicated at 3^e (Fig. 7) so that in one position of the channel bars 6 the serrations 6^a project into the grooves G as shown in Fig. 3 and in the other position of the bar 6 these serrations will lie between the grooves and out of the way of the balls as shown in Fig. 11. These plates 6, I term ball-locking members and stops hereinafter explained.

The lock bars 6 may be made to rise simultaneously with their reciprocations so as to cause the serrations 6^a to project more fully into the groove G (see Fig. 3) by any suitable means. As shown, the plate 2 may be provided with upwardly inclined lugs 2^c struck up therefrom (see Fig. 3) which are adapted to engage correspondingly inclined lugs 6^c struck up from the bottom of the bars 6 so that when the bars are moved in one direction to project the serrations 6^a into grooves G the bars 6 ride up on the lugs 2^c (see Fig. 3) and when moved in an opposite direction to withdraw the serrations 6^a from the grooves G, as in Fig. 11, the bars 6 descend. These bars 6 are moved longitudinally at the proper times by the means hereinafter described.

In the apexes of the corrugations of the plate 4 are formed series of slots 4^b (Figs. 2 and 11) which are spaced equidistantly lengthwise of the grooves G. At what I call the rear side of the ballot-marker there is a permanent stop 3^c (Fig. 7) located in the grooves G adjacent the rearmost row of slots 4^b in the plate 4. This stop 3^c prevents the rolling of any ball farther down the groove G than the rearmost row of slots 4^b.

The number of the corrugations or grooves G and the length of these grooves and numbers of the openings 4^b therein will vary according to the size of the ballot and number of candidates it is intended to be voted for on the ballot and obviously almost any desired number can be provided by sufficient number of ball grooves and number of openings therein.

Slidably mounted upon the plate 4 is a corrugated plate 5 which corresponds in size and contour with the plate 4 and this plate is provided with slots 5^b (Fig. 3) in its ridges which are adapted to register with the slots 4^b (Fig. 11). The plate 5 may be held in slidable engagement with the plate 4 in any suitable manner.

As shown, the plate 5 is slidably supported by and upon the plate 4. The plates 3 and 4 are connected together at their ends and fixedly attached to the frame at their rear side (Fig. 7) or otherwise supported in the frame to be fixedly mounted therein. As shown in Figs. 8 and 9, the plate 5 is connected to strips 5^e which depend through slots in the plate 2 and are pivotally engaged with the adjacent ends of levers 7 which are pivoted at 7^a on the bottom plate 2 and the inner ends of the levers 7 overlap. To one of these levers is attached a pin 7^c which is engaged with a slot 7^d in the other lever and the other end of this pin engages a cam slot in a cam disk 7^e, which is pivoted on the plate 2 at 7^f and has a pin 7^g which engages a slot 8^a in a slide bar 8 which is suitably guided in the side of the frame and extends near one end thereof (see Fig. 9) and this slide bar has a flange 8^b provided with a perforation 8^c which is adapted to be engaged by a pin 27^a (Fig. 16) on a ballot-handling machine when the ballot-marker is placed in said machine as hereinafter described. The sides of the plate 5 may be stiffened by beading them as indicated at 5^b in Fig. 7—so that the plate will not buckle.

The locking bars 6 may be moved at the proper time by suitable mechanism. In the form shown in the ballot each bar 6 is connected with actuating light spring members 6^c (Figs. 3 and 11) which project beyond one end of the bar and each has a head 6^d on its outer end which has a perforation for the reception of a pin 6^h (Fig. 4) attached to the upper side of a ring 6ⁱ. Each ring 6ⁱ

has a pin 6^j on its lower side almost diametrically opposite pin 6^h which pins 6^j are adapted to engage lugs 6^k on a sliding plate 6^m (see Fig. 4) for a purpose hereinafter described. This bar 6^m is longitudinally movable and to one end thereof is attached a plate or member 6ⁿ which depends through an opening in the plate 2 and has a perforation 6° (see Figs. 8-9) which is adapted to be engaged by an actuating member 16^s (Fig. 14) in the ballot-handler hereinafter referred to. When the slide 6^m is moved in one direction it will turn the rings 6ⁱ and pins 6^j and 6^h causing the bars 6 to move in one direction outward to the position indicated in Fig. 11, the rings 6ⁱ being confined against lateral movement. Each head 6^s is provided with a projecting member 6^p which is adapted when the bar is in position shown in Fig. 11 to project through an aperture 1^p in the adjacent end of the casing. This projection may be of any suitable construction being shown as a U-shaped piece of metal secured to the head 6^s. The bars 6 may be independently moved inward as hereinafter described by mechanism in the ballot-marker and to insure that they shall all be moved inward before the ballot is removed from the ballot-handler as hereinafter explained means may be provided for throwing in any bar 6 which may not have been moved in when the voter was making up his ballot. For this purpose, in the construction shown, each head 6^s carries a pin 6^r which is adapted to engage the cam surface 6^t of a slidable cam plate 6^t, (see Figs. 10-11) which lies parallel with and above the plate 6^m. This plate has a series of slots in its inner side, one side of the slots being inclined at 6^s as shown in Fig. 10. In the normal position of the plate the slots will permit the free movement of the pins 6^r inward or outward; but when the bar 6 is moved outward by the action of the plate 6^m the pins 6^r will engage surfaces 6^s and move the bar 6^t slightly upward and the end of this bar will project through an opening 1^t in the side of the frame 1 (see Fig. 10). Before the ballot can be removed from the ballot setting machine this bar 6^t will be pushed inward (see Fig. 18), thus insuring that every bar 6 will be moved inward in the locked position.

At the front of the frame and adjacent the front ends of the plates 3 and 4 is a guideway for a series of balls B; there being one ball B for each groove G, and these balls being adapted to enter these grooves G from the outer or front ends thereof. This ball holding guideway may be provided by any suitable construction of parts and the balls are preferably yieldingly contained in such guideway but may be forcibly pushed therefrom into the adjacent ends of the grooves G. In the construction shown, (see Figs. 2 and 7) the guideway is formed between the

upper edges of a longitudinally disposed Z-shaped plate 9 which may be supported upon the plate 2 (see Fig. 7) and the upper edge of a spring plate 9^a which may be fastened to a rod 9^b extending parallel with the plate 9. The inner upper edge of the plate 9^a is slotted so as to form a series of slight spring tongues 9^c near opposite ends of each groove G and these springs tend to prevent the balls B entering the grooves by gravity, but will permit the ball to be pushed laterally from the guideway into such groove.

Attached to the shaft 9^b are arms or depending fingers 9^s which extend through slots in the plate 2 but terminate above the plate 1^a, the free ends of the fingers 9^s lying opposite slots 1^s in the plate 1^a. These fingers are adapted to be engaged by devices on the ballot-handler hereinafter described when the ballot is placed thereon. The fingers 9^s are normally pressed by springs 9^t (see Fig. 7) in such direction that the tongues 9^c on the plate 9^a will prevent the entrance of the balls B into the grooves G; these tongues 9^c, however, permit the balls to be pushed thereover into the groove.

The balls B are prevented from being moved out of the ballot-marker, being loosely confined therein by the inner edge of the plate 9 and the lower edge of a flange 4^s on the front end of the plate 4 (see Fig. 7). When the ballot-marker is removed from the ballot-handler the balls should be covered by any suitable means so the arrangement thereof cannot be seen and they can not be tampered with. The cover may be of any suitable kind. In the construction shown in Fig. 7 a cover plate 12 is hingedly mounted to the upper end of the flange 4^s and this plate may be pivotally connected by the offset ends of the hinge-pin (Fig. 2) to one end of lugs 12^a connected at 12^b to the end of the adjacent bead 5ⁿ on the plate 5. When this plate 5 is moved rearwardly the cover 12 is closed as shown in Fig. 7, but when the plate 5 is moved outwardly the cover will be raised. In the normal position of the parts the cover plate 12 is closed and the means for shifting the balls B on the ballot-marker is mounted upon and will be described in connection with the ballot-handler by which the voter is enabled to adjust the ball to vote.

The balls may be spaced apart opposite each groove by means of small spacing plates 9^d (Fig. 2) which may be guided in transverse slots in the upper portion of the Z bar 9 (see Figs. 7-12). These plates may be locked in position by any suitable means. As shown they are locked in position by means of lugs 10^e struck up out of a plate 10 which is slidably connected to the Z plate 9 as shown in Fig. 7. The plate 10 can be slid up manually so as to bring the lugs 10^e out of register with the spacing plates 9^d. The plates 9^d may be provided with lugs 9^e which can register with

- the lugs 10^e, (see Fig. 12) so as to lock the spacing plates 9^d in position, but the bar 10 can be moved manually so as to bring the lugs 10^e out of register with the lugs 9^e and when thus positioned any of the spacing plates 9^d may be moved outward as indicated in Fig. 12 for the purpose of permitting group voting as hereinafter explained. After the spacing plates 9^d are properly adjusted for group voting the bar 10 is returned to normal position thus locking out the spacing plates 9^d moved outward for group voting and locking in the remaining spacing plates 9^d for single voting.
- 15 The ballot-marker is provided with means for voting on "yes" or "no" propositions such as constitutional amendments or other matters which require only an affirmative or negative vote.
- 20 As shown in Figs. 2, 7, and 13, within the ballot frame at the rear side thereof and back of the plates 4 are two longitudinal supporting plates 11 and 11^a which are suitably supported in the frame and extend longitudinally thereof: and upon these plates are supported balls B' which are suitably spaced apart. Each of these balls B' is confined in a U-shaped groove G' formed in the upper end of a plate 11^b secured in the frame (see Figs. 7 and 13). The upper part of this plate lies above the upper sides of the plates 11, 11^a, and each ball B may roll in its groove G' from one end thereof to the other. The balls are movably confined in the grooves by means of a top plate 11^c and in this top plate, above and at opposite ends of each groove G', are slots or openings 11^d and 11^e; and in said top plate is a slot 11^f, at the center bend of each groove G'. Each ball B' can move in its slot by gravity, but its normal position is at the center of the slot G'; and it may be detained in this position by a hole 11^g in the plate 11. Extending longitudinally of and between the plates 11 and 11^a is a slide-bar 11^h the upper end of which is provided with serrations or teeth 11ⁱ which in the normal position of the plate (see Fig. 13) will not register with the slot G' and will not interfere with the movement of the ball in said slot. In the other position of this plate 11^c these serrations will project into these slots and prevent movements of the balls in the slot. This bar 11^h is provided with a head 11^j at one end which head 11^j is similar to the heads 6^g connected to bars 6. This head has a push piece 11^p (corresponding to the push pieces 6^p) and is provided with a pin 6^h engaging a ring 6ⁱ which ring is operated by the bar 6^m in the same manner as the other rings 6ⁱ are operated. The head 11^j also has a pin 6^g adapted to be engaged by the cam on the plate 6^t so that the bar 11^h can be operated as are the channel bars 6 as above described. The ball may be moved to either end of the slot G' so as to appear beneath either of the openings 11^d, 11^e. The balls may be moved

in the slot by any suitable means but preferably by devices on the ballot handler as hereinafter described and in the present invention the ball can be moved only when the ballot-marker is properly positioned in the ballot-handler and by the means provided on the ballot-handler; the balls being locked against movement in the grooves G' when the ballot is removed from the machine.

The ballot-handler or setter.

The ballot handler or setter comprises a base 14 (Figs. 1, 14 and 16) which may be of any suitable construction and is adapted to support the ballot in various positions and carry certain operative parts. It is preferably stamped out of sheet metal, such as aluminum for the purpose of lightness, and it approximately corresponds in exterior dimensions to the exterior dimensions of the ballot-marker. This base 14 is pivotally supported so as to be tiltable longitudinally upon axially disposed pivots. As shown, it is pivoted at 14^a on any suitable support as 15^a which may be placed upon a table 15 or other convenient support where it may be attached for the voter. Extending longitudinally of the support 14 is a rod 16 which is rotatably mounted in the end members of the frame or bearings attached to the plate 14 and has a crank or handle 16^a on one end by which it can be easily rocked. To this shaft 16 are fixedly attached arms 16^b the free ends of which are pivoted to links 16^c, the other end of which links are pivoted to brackets or ears 15^b. The links 16^b and 16^c form toggles which may be broken or extended by locking shaft 16 and when extended these toggles will hold the plate 14 in the position shown in full lines in Fig. 14 and when broken the support will be moved to the position indicated in dotted lines in said Fig. 14. On this shaft 16 near each end thereof are fastened short fingers 16^d which are adapted to project through slots 14^d in the supporting plate 14. When a ballot-marker is in position on the plate 14 the slots 1^s (Fig. 7) in the plate 1^a will register with the slots 14^d in the plate 14 and when the shaft 16 is rocked, the fingers 16^d engaging the fingers 9^s on the shaft 9^b will rock said shaft so as to lower the plate 9^a and permit all the balls to roll back out of the grooves G into position in the guideway above the plate 9^a shown in Fig. 7; but as soon as the shaft 16 is rocked so as to disengage fingers 9^s springs 9^t will rock shaft 9^b and cause plate 9^a to engage and retain the balls yieldingly in position indicated in Fig. 7 ready for manipulation by the voter.

On shaft 16 is another arm 16^e which is connected by link 16^f to one end of a lever 16^g which is pivoted at 16^h on a lug or member attached to the supporting plate 14 and the free end of this lever 16^g is adapted to project through a slot 14^e and will also project through a slot in the bottom plate 1^a and en-

gage the opening 6^a in the member 6^a and move the slide 6^m in a direction so as to cause all the ball locking bars 6 to be retracted into position shown in Fig. 11 and free the grooves 70 G so that the balls may return to voting position. The supporting plate 14 is provided at the rear with corner pieces 14^c which serve to position the rear side of the ballot-marker correctly upon the support 14 when it is placed 75 thereon and support 14 is provided with front ears or plates 14^b which serve to position the front edge of the ballot-marker on the support when it is placed thereon.

Hingedly connected with the support 14 in 80 any suitable manner is a ticket carrying frame which approximately corresponds in its interior contour with the exterior contour of the ballot-marker. As shown, this frame comprises a front member 17 (on which are 85 mounted the devices for projecting the balls B into the grooves G); a rear bar 18^b (on which may be mounted the devices for operating the ballot-marker; the devices for shifting the balls B' in the grooves G'); and the 90 device for positively locking all bars 6 before the ballot-marker can be removed from the ballot-handler a member 19 (Figs. 1 and 16) on which are mounted the devices hereinafter referred to, and an end member 20 on which 95 are mounted the adjusting levers also hereinafter referred to. In the construction shown, the frame is hinged to the supporting plate 14 by means of hinged members 18^a connected to lugs or plates 14ⁱ attached to the 100 support 14 and projecting at the rear side thereof.

Extending longitudinally of the ticket carrying frame and pivotally mounted in the end bars 19 and 20 are a series of parallel 105 ticket carrying strips or bars 21. Each of these bars is adapted to carry in column form a ticket which substantially corresponds to a section of the common or Australian ballot; there being as many of these strips used as 110 there may be columns in the ballot-marker or number of party tickets in a given election and in the example shown I have merely illustrated two such ballots in position in Fig. 1 but obviously any number of these ballot 115 strips may be used and their length may be varied to suit the size of the ballot-marker. The ballot-marker and the ballot-handling or setting devices would be made to suit the proposed requirements of the city or municipality using such machine. It can be seen that the number of these ticket strips and the 120 length of such strips depend entirely upon the maximum number of individual candidates and the number of tickets to be printed for any given municipality or city. The tickets 125 may be applied to the strips 21 in any desired way as by being pasted thereon or otherwise attached to the strips; this forming no part of the present invention. In the example shown, the strips are detachable. Each is

provided at one end with a lug 21^a (Fig. 1) which is adapted to engage a perforation 19^a in the bar 19 and its other end is adapted to be engaged in a slot 22^a on the head of the ticket turning lever 22 pivoted to the bar 20 there being one such lever for each ticket carrying strip employed in the ballot-marker, so that when the strips are in place they are arranged parallel and side by side as indicated in Fig. 1. Each ticket turning lever has a head 22^b 75 which is pivoted to the member 20 by a pin 22^c and each lever has a finger piece 22^d on its outer end and is provided with a rounded cam like projection 22^e below said finger piece on its upper end. The first or rearmost of the levers 22^a is pivotally connected by a link 22^f (Fig. 14) to the upper end of a lever 23 pivoted on the member 20 near the rear end thereof and hereinafter referred to. The pin 23^a connecting lever 23 to link 22^f is slidably engaged with a slot 24^a in a lever 24—which lever is pivotally connected to one arm of a lever 24^b mounted on the rod 18^b and the other arm of this lever 24^b is pivotally connected to one end of a link 24^c connected to the ear 15^c 80 on base 15.

This construction is such that if the ballot-handler is turned to the position indicated in dotted lines in Fig. 14 the link 24^c through the levers 24^b and 24 will engage the pin 23^a and through this pin the lever 23 and the rearmost lever 22 will be turned toward the bar 17 of the ballot-marker. At the same time each cam portion 22^e on each lever 22 will engage the adjacent lever 22 and thus all these levers 100 will be simultaneously moved in the same direction.

The ticket carrying strips are designed to carry on one side the names of the candidates and on the other side the names of the office so that when in voting position the rear strip when turned toward the rear as shown in Fig. 1 would show the names of the candidates while the next adjacent strip which is turned to the front of the device would show the name of the office for which each candidate is running and when the voter has registered his vote for the candidates on the first strip which we call strip C, Fig. 1, he will turn the second strip B, Fig. 1 to the right and then on the reverse side of the strip B (not shown) will be found the names of candidates for another party and on the reverse side of the next adjacent strip (not shown) would appear the same offices, the offices on the several strips being the same.

When the ballot-marker is first placed in the ballot-handler or setter the parts are in the position shown in full lines in Fig. 14.

Attached to the bar 18^b of the ballot-handling frame is a plate 18^k (Fig. 1) which carries a "yes" or "no" ballot support 18ⁱ which projects above and in rear of the bar 18^b and opposite the series of grooves G'. This plate 130 may be of any desired length to carry any de-

sired number of ballots for "yes" and "no" questions as the ballots are so printed that the "yes" on the ballot will be adjacent the slot 11^d at the end of one of the grooves G' and the 5 "no" on the ballot will be adjacent slot 11^e of said groove.

The lever 23 when in the position shown in Fig. 14 should come opposite the projection 11^p on the locking bar 11ⁱ of the "yes" and 10 "no" ballot. This lever 23 has a cam 23^k (Fig. 15) which would come opposite the projection 11^p. The heads 22^b of the levers 22 lie opposite the projections 6^p on the locking bars 6. Each of the heads 22^b has a cam 22^k (Fig. 15) 15 which is adapted to engage the adjacent projection 6^p.

When the bars are in the position shown in Fig. 14 the cams 22^k and 23^k of the respective levers 22 and 23 would not engage the projections 11^p and 6^p but if any of these levers are turned backward or to the left then the cams on such lever would engage the related projection 11^p or 6^p and push the locking bar inward to locking position thereby locking 20 the balls used for voting on this particular strip as hereinafter explained.

When the ballot-marker is placed in the ballot-handler in the position shown in Fig. 14 the voter will first vote the "yes" or "no" 30 proposition. For this purpose the balls B' in the related grooves G' opposite the ballot indicated in Fig. 1 must be voted. For this purpose I provide the ballot-frame with simple devices whereby any ball B' may be 35 moved right or left. As shown, a plate 25 (Fig. 17) is slidably engaged with the rear bar 18 of the ballot-handling or setting frame and to this slide is attached a forwardly projecting plate 25^a which is adapted to project 40 above the slotted plate 11^e and this plate 25^a is provided with two openings 25^d and 25^e (Fig. 1), which are so spaced apart that if the slide be moved so that the slot 11^d is visible through the related slot 25^a, the slot 11^e will 45 not be visible through its related slot 25^e, see Fig. 1. Said plate 25^a is also provided with two openings 25^b and 25^c through which the "yes" or "no" on the ballot can be discerned but when the plate 25 is adjusted so 50 as to disclose the "yes" the "no" would be covered and if the "no" could be seen through opening 25^c the "yes" would be covered. When this plate is adjusted so that the "yes" or "no" is visible to the voter the plate is then 55 properly positioned ready for the voter to shift the ball in the groove G' and to shift the ball the plate is provided with a guide 25^f through which passes a push finger 25^g having a pointed lower end and having a finger 60 piece on its upper end, its side being normally raised by a spring 25^h. This finger is so located on the plate that when the slide is properly adjusted to disclose either the "yes" or "no" on the ballot the finger would be directly 65 above the related slot 11ⁱ and the point of

the finger slightly to the right or left of the ball. If the voter depresses the finger, the ball B' will be forced to right or left into position beneath the exposed opening 11^d or 11^e corresponding to the exposed "yes" 70 or "no" on the ballot and will lie in this position by gravity and will be locked in this position by the shifting of the bar 11^h through the action of the cam 23^k on the lever 23 against the projection 11^p of the locking 75 bar 11ⁱ.

After the voter has registered his "yes" or "no" questions as above stated he then turns the first or rearmost lever 22 from the position shown in full lines in Fig. 14 backward to the position shown in full lines in Fig. 1 thereby disclosing the names of the candidates to be voted for on the first ticket carried on the back of the next ticket carrying strip 21 as shown in Fig. 1. When the 80 voter moves this first lever 22 he also moves the lever 23 and thereby causes the bar 11^h to lock the balls B' in the "yes" or "no" voting grooves.

When adjusted for voting the first ticket, 90 the voter must push a ball into the grooves G opposite the names of each candidate for whom he wishes to register a vote on the first ticket. To do this the balls are pushed from the position shown in Fig. 7 into each related 95 grooves by pushing them inward over the spring fingers 9^c and the balls are then rolled by gravity down the groove and against the stop 3^c. These balls are pushed into the grooves by any suitable means. In the construction shown, I have provided a bead 17^a (Figs. 1 and 14) attached to the upper edge of the front bar 17 of the ballot-handler and a sleeve 26 is slidably engaged with this bead. To the sleeve is attached a pointer plate 26^a 100 which has a slot or notch 26^b corresponding in width to one of the grooves G and this plate can be adjusted longitudinally of the frame opposite any one of the slots G and can be depressed so as to engage a ball in the 105 position shown in Fig. 7 and when so engaged the ball can be pushed into the slot G by means of pusher 26^e normally held outward by a spring 26^d. By this device, any ball or number of balls can be quickly and 110 readily projected into the slots G.

The grooves G are numbered in succession from the top to the bottom of the ballot-marker and the numbers of these grooves appear on the upper, outer edge of the ballot-marker adjacent the strip 9 as indicated in Fig. 1. These numbers may be applied in any suitable way. The printed ballot and number of candidates on the strip correspond in number with the grooves G with which they 115 register.

Ordinarily, each ball B would have to be separately manipulated by the device described to project it into the related groove G; but where a number of candidates are to be 120

voted for in so called "group-voting", the ball spacing members 9^a can be adjusted as shown in Fig. 12 so as to permit the balls in this group to be moved forward to the same 5 groove so that the voter can successively push a number of balls into the same groove, the balls in the group being successively projected into the groove as and after the successive ballot strips are turned by successively moving the levers 22.

After the voter has registered his votes for the candidates on the first strip 21, he moves the second lever 22 backward so that the strip B would then overlie the strip C,

15 the cam 22^b on this second lever engages the projection 6^b on the first or rearmost channel bar 6 and the latter is raised to the position shown in Fig. 3. In this position, the rear flange 6^a on the locking-bar 6 locks the first 20 ball B for the first number of candidates in position against the stop 3^c, while the forward flange of said locking-bar comes into position to act as a stop to stop the ball beneath the next related row of slots 4^b. When 25 the ballot-marker is out of the ballot-handler, the plate 5 is shifted so that the slots 5^b are out of register with the slots 4^b and therefore nothing can be seen as to the position of the 30 balls in the ballot-marker. The ballot-marker is placed in the ballot-handler while the frame of the ballot-handler is in raised position, indicated in dotted lines at the extreme left of Fig. 14. Then the frame is lowered. When the ballot-marker is placed 35 in the ballot-handler, the perforation 8^c (Fig. 9) in the plate 8^b fastened to the bar 8 is engaged by a hook or projection 27^a (Fig. 16) on an arm 27^b attached to a plate 27 slidably mounted under the supporting plate 14. This 40 supporting plate is connected with a slide 28 which projects beyond the end of the said supporting plate 14 and, as shown, is provided with a pin 28^a, which is adapted to be engaged by a cam 28^b attached to the rod 18^b 45 so that when the frame is raised the cam pushes the slide 28 and finger 27^a inwardly. A second opposed cam 28^c is also attached to the frame and is adapted to engage the roller 28^a when the frame of the ballot-handler is 50 lowered thereby pushing the plate 28 and finger 27^a outward. When the ballot is placed in the ballot-handler, the finger 27^a engages the perforation 8^c in the plate 8^b attached to the bar 8; and when the ballot-handling 55 frame is lowered the finger 27^a moves the plate 8 to the right (Fig. 9) and thereby causes return of the levers 7 and causes the plate 5 to be moved forwardly to register the slots 5^b with the slots 4^b.

60 After the voter has completed his ballot, it is necessary that all the locking-bars 6 which have not been moved into locked position by the turning of the ticket strip carrying levers 22 be locked before the ballot-marker may be removed from the ballot-

handler or setter. For this purpose, (as shown in Fig. 18) the rod 18^b is provided with a cam 29 opposite the exposed end of the locking plate 6^c. When the frame of the ballot-handler is raised to the position shown in 70 dotted lines at the extreme end of Fig. 14, the cam 29 is adapted to contact with the locking plate 6^c moving said plate to the position shown in Fig. 10 and then, by the action of the cam surfaces 6^a against the pins 6^c, all 75 of the locking-bars 6 not previously shifted inward will be moved inwardly into locked position.

What I claim is:

1. In voting means of the character described, a ballot-marker provided with a plurality of grooves, members adjustable in said grooves, and means whereby the members may be locked in adjusted positions in the grooves, substantially as described. 80

2. In voting means of the character described, a ballot-marker provided with a plurality of grooves, members adjustable in said grooves, means whereby the members may be locked in adjusted positions in the grooves, 85 and means whereby the members will be locked out of the grooves in non-registering positions prior to their setting by the voter. 90

3. A ballot-marker as set forth in claim 2 means whereby any member adjusted by the 95 voter will be locked in position after he has set the same.

4. In a ballot-marker as set forth in claim 2, means whereby the ballot-marker is normally locked before the voter has voted, and 100 whereby the parts are locked after the voter has voted so that the ballot may not be tampered with either before or after the voter has voted.

5. In a ballot-marker as set forth in claim 2, 105 means whereby any member adjusted by the voter will be locked in position after he has set the same; and means whereby the ballot-marker is normally locked before the voter has voted, so that the ballot may not be 110 tampered with either before or after the voter has voted.

6. In balloting mechanism a ballot-handler and marker provided with adjustable devices whereby the voter may indicate each candidate for whom he desires to vote; and a ballot handling mechanism adapted to receive the ballot-marker, and means whereby when the ballot is properly placed in the handler it is opened and the adjustable devices may be 115 adjusted by the voter and whereby before the ballot can be removed from the handler the said devices are locked and the ballot sealed. 120

7. In voting means of the character described, a ballot-marker provided with a plurality of grooves, members adjustable in said grooves, means whereby the members may be locked in adjusted positions in the grooves, with a ballot-handler adapted to receive the ballot, and means whereby when the ballot 125 130

is properly placed in the handler; the handling devices may be adjusted by the voter and whereby before the ballot-marker can be removed from the handler the parts are 5 locked and sealed.

8. In voting means of the character described, a ballot-marker provided with a plurality of grooves, members adjustable in said grooves, means whereby the members may be 10 locked in adjusted positions in the grooves, and means whereby the members will be locked out of the grooves in non-registering positions prior to their setting by the voter; with a ballot-handler adapted to receive the 15 ballot, and means whereby when the ballot is properly placed in the handler; the setting devices may be adjusted by the voter and whereby before the ballot-marker can be removed from the handler the parts are locked 20 and sealed.

9. In voting means of the character described, a ballot-marker provided with a plurality of grooves, members adjustable in said grooves, means whereby the members may be 25 locked in adjusted positions in the grooves, means whereby the members will be locked out of the grooves in non-registering positions prior to their setting by the voter; means whereby any member adjusted by the voter 30 will be locked in position after he has set the same; means whereby the ballot-handler is normally locked before the voter has voted, and whereby the parts are locked after the voter has voted so that the ballot may not be 35 tampered with either before or after the voter has voted; with a ballot-handler adapted to receive the ballot, and means whereby when the ballot-marker is properly placed in the handler; the handling devices may be adjusted 40 by the voter and whereby before the ballot-marker can be removed from the handler the parts are locked and sealed.

10. In voting means of the character described, a ballot-marker provided with a plurality of grooves, members adjustable in said 45 grooves, means whereby the members may be locked in adjusted positions in the grooves, means whereby the members will be locked out of the grooves in non-registering positions 50 prior to their setting by the voter; means whereby any member adjusted by the voter will be locked in position after he has set the same; means whereby the ballot-marker is normally locked before the voter has voted, so 55 that the ballot may not be tampered with either before or after the voter has voted; with a ballot-handler adapted to receive the ballot, and means whereby when the ballot is properly placed in the handler; the handling devices 60 may be adjusted by the voter and whereby before the ballot-marker can be removed from the handler the parts are locked and sealed.

11. In voting means of the character 65 described, a ballot marker provided with a plu-

rality of grooves, balls adjustable in said grooves, and means whereby the balls may be locked in adjusted positions in the grooves, substantially as described.

12. In voting means of the character de- 70 scribed; a ballot-marker provided with a plurality of grooves, members adjustable in said grooves, means whereby the members may be locked in adjusted positions in the grooves, means whereby the members will be 75 locked out of the grooves in non-registering positions prior to their setting by the voter; and means whereby any member adjusted by the voter will be locked in position after he has set the same. 80

13. In combination with a ballot-marker as set forth in claim 6, a ballot setter adapted to receive the ballot, and means whereby when the ballot is properly placed in the setter; the setting devices may be adjusted by the voter 85 and whereby before the ballot-marker can be removed from the setter the parts are locked and sealed.

14. In combination with a ballot-marker as set forth in claim 11, a ballot setter adapt- 90 ed to receive the ballot, and means whereby when the ballot is properly placed in the setter; the setting devices may be adjusted by the voter and whereby before the ballot- 95 marker can be removed from the setter the parts are locked and sealed.

15. In combination with a ballot-marker as set forth in claim 12, a ballot setter adapt- 100 ed to receive the ballot, and means whereby when the ballot is properly placed in the setter; the setting devices may be adjusted by the voter and whereby before the ballot- 105 marker can be removed from the setter the parts are locked and sealed.

16. In voting means of the character de- 105 scribed, a ballot-marker provided with a plurality of grooves, balls adjustable in said grooves, means whereby the balls may be locked in adjusted positions in the grooves, means whereby the balls will be locked out 110 of the grooves in non-registering positions prior to their setting by the voter; means whereby any ball adjusted by the voter will be locked in position after he has set the same; and means whereby the ballot setter 115 is normally locked before the voter has voted, and whereby the parts are locked after the voter has voted so that the ballot may not be tampered with either before or after the voter has voted. 120

17. In balloting mechanism a ballot holder and marker provided with adjustable balls whereby the voter may indicate each candidate for whom he desires to vote; and a ballot setting mechanism adapted to receive the ballot, and means whereby when the ballot-marker is properly placed in the setter it is opened and the balls may be adjusted by the voter and whereby before the ballot can be removed from the setter the said balls are 125 130

locked and the ballot sealed in their places.

18. A ballot-marker having a series of transverse grooves, a ball for each groove, and adjustable means for arresting the ball 5 in any desired position in the groove.

19. In a ballot-marker having a bottom plate provided with a series of grooves, balls in the grooves, a pair of grooved top plates having openings adapted to register to show 10 the position of the balls, and means for relatively shifting the top plates to move the openings therein out of register.

20. In a ballot-marker having a series of transverse grooves, a ball for each groove, 15 members underlying the grooves and having portions adapted to be projected thereinto when the members are in one position and means for moving the members so as to cause the said portions to project into the 20 grooves.

21. In a ballot-marker having a series of transverse grooves, and balls in the grooves, bars underlying the grooves and having portions adapted to be projected thereinto when 25 the bars are in one position and means for moving the bars so as to cause the said portions to project into the grooves.

22. A ballot-marker having a series of grooves, balls adapted to enter the grooves; 30 and adjustable ball spacers whereby the balls may be kept separate opposite their respective grooves or whereby a number of adjacent balls may be permitted to be moved to the same groove.

23. A ballot-marker having a series of parallel grooves, means for projecting a ball into each groove, a series of transversely movable devices for arresting the balls at desired 35 points in the grooves, and means for locking the balls when properly placed in the grooves.

24. A ballot-marker having a base plate, provided with transverse grooves and slots intersecting the grooves, a series of channel 45 bars arranged transversely of and below the plate having portions adapted to project through the slots into the grooves; a ball channel adjacent the grooves, a series of balls in said channel, one for each groove; 50 and means for moving the channel bars into or out of ball arresting position.

25. In a ballot-marker as set forth in claim 24, having a base plate provided with a pair of grooved top plates overlying and registering with the grooves by the base plate to guide the balls, said top plates being perforated so as to disclose the balls when the perforations register, and means for shifting the top plates into or out of register.

26. In a ballot-marker having a plurality of U-shaped grooves at one side adjustable members in said grooves, means whereby any members may be moved to either end of its groove; and means whereby when the 60 members are so shifted they are locked in

such position until the ballot is registered.

27. In combination with a ballot-marker having a series of grooves and movable devices adapted to be adjusted in said grooves; means for locking such movable devices in 70 the grooves; and longitudinally movable bars for arresting the devices in said grooves; a rocking ballot strip, a lever for actuating said strip, and means whereby when the lever is turned the said locking devices are actuated. 75

28. A ballot-marker having a U-shaped groove, a ball in the groove, and means whereby the ball may be moved to either end of the groove, and means for locking the ball 80 in adjusted position.

29. In a ballot-marker having a series of U-shaped grooves at one side, balls in said grooves, adjustable devices whereby any ball may be moved to either end of its groove, and means whereby when a ball is so shifted it is 85 locked in such position until the ballot is registered.

30. In combination, a ballot-marker provided with a plurality of grooves, adjustable members in said grooves, and means whereby the members are locked in adjusted position 90 in the grooves; with a ballot setter adapted to receive the ballot-marker, means on said setter whereby the ballot-marker is unlocked when it is placed in the setter; pivoted ballot displaying members on the ballot setter and means on the ballot setter whereby when the ballot displaying devices are turned the related ballot setting devices will be locked. 95

31. A ballot setter having a tiltable base 100 adapted to support a ballot-marker, a swingable hinged frame upon the base, ballot displaying devices mounted on this hinged frame, and means on the ballot displaying device whereby the related marking devices 105 of the ballot-marker will be locked when a ballot displaying device is shifted, substantially as described.

32. In voting means of the character described the combination of a ballot marker; with a ballot setter having a tiltable base to support the ballot-marker, means for tilting this base to rock the ballot-marker thereon, and means on the setter whereby when it is 110 tilted in one direction the ballot-marker is locked and means on the setter member when the base is tilted in the opposite direction the ballot-marker is released. 115

33. In combination with a ballot-marker, a ballot-setter having a hinged frame, a series of tiltable swingable levers mounted thereon, and cams carried by said levers adapted to operate related devices on the ballot-marker, when the latter is inserted in the ballot setter. 120

34. In combination with a ballot marker, a ballot setter having a hinged frame, a series of tiltable swingable levers mounted thereon; ballot strips removably attached to opposite levers so as to be tilted thereby, and cams carried by said levers adapted to operate 125 130

related devices on the ballot marker, when the latter is inserted in the ballot setter.

35. In a ballot setter, a series of parallel swingable ballot strips; adjacent ballot strips respectively bearing on their opposed faces the names of the offices and of the candidates for such offices, whereby when one strip is

turned from one position to the other, another set of candidates will be displayed to the voter.

In testimony that I claim the foregoing as my own, I affix my signature.

EUGENE GREGORY.
